(57) **CLAIM**

The ornamental design for a pharmaceutical dosage form, as shown and described.

DESCRIPTION

FIG. 1 is a perspective view of a pharmaceutical dosage form showing our new design.

FIG. 2 is a front view of the pharmaceutical dosage form shown in FIG. 1.

FIG. 3 is a bottom view of the pharmaceutical dosage form shown in FIG. 1.

FIG. 4 is a top view of the pharmaceutical dosage form shown in FIG. 1.

FIG. 5 is a right side view of the pharmaceutical dosage form shown in FIG. 1; and,

FIG. 6 is a left side view of the pharmaceutical dosage form shown in FIG. 1.

The dashed lines in FIGS. 1 to 6 represent environmental structure and form no part of the claimed design.
